UNITED STATES PATENT OFFICE.

HANS NICOLAUS CLAUSEN AND FRED CLAUSEN, OF STACYVILLE, IOWA.

DESIGN FOR A SCOURING-BOX.

SPECIFICATION forming part of Design No. 24,669, dated September 10, 1895.

Application filed May 27, 1895. Serial No. 550,869. Term of patent 14 years.

To all whom it may concern:

Be it known that we, HANS NICOLAUS CLAUSEN and FRED CLAUSEN, citizens of the United States of America, residing at Stacyville, in the county of Mitchell and State of Iowa, have invented a new and original Design for a Scouring-Box, of which the following is a specification.

Our invention consists in the design for a box, as hereinafter set forth, pointed out in our claim, and illustrated by the accompanying drawing, in which the view is a perspective of the complete device and design therefor.

The leading feature in our box design is in a bottom in two planes, one plane 10 being horizontal and the other plane 11 being inclined. One end of the inclined plane is above and adjacent to the horizontal plane, and a vertical plane portion 12 connects the same, and the opposite end of the inclined plane aligns with horizontal portion 10.

Another feature of our box design is in a partition 13, transversely of the inclined portion of the bottom, which partition has a sinuous upper edge 14, of symmetrical outline, projecting at two points 15 16 above the box sides hereinafter mentioned. Another feature of our box design is in vertical portions 17 18 at either end of the bottom. The vertical portion 17 is of materially greater height than the portion 18.

Another feature of our design is in the sides of the box formed with ends 19 20 of different widths and with sinuous upper edges. The narrow end 19 of the sides corresponds in width with the vertical portion 18, and the wider end 20 of said sides corresponds in width with the vertical portion 17 of the box. The sinuous upper edges of the 40 sides of the box are symmetrical in design and have angular bends adjacent to the partition 13 and abrupt curved bends adjacent to and above the higher end of the bottom. The vertical portion 18, the partition 13, wide end 45 portions of the sides, and a portion of the inclined bottom form a receptacle for the scouring material. The remainder of the inclined bottom is employed as a scouring bed or support for the articles being scoured. The vertical portion 12, horizontal portion 10, vertical portion 18, and narrow ends of the sides form a receptacle for the scouring-tool.

We claim as our invention—

The design for a scouring box as herein 55 shown and described.

HANS NICOLAUS CLAUSEN.
FRED CLAUSEN.
